UNITED STATES PATENT OFFICE

THOMAS WILSON HARTLEY, OF OAKEN, NEAR CODSALL, WOLVERHAMPTON, ENGLAND

MACHINE FOR STRAIGHTENING RODS AND PIPES

Application filed June 4, 1930, Serial No. 459,177, and in Great Britain June 12, 1929.

This invention relates to machines for straightening rods and pipes and particularly concerns machines which comprise a frame in which are arranged a plurality of passes [5 (two passes usually being employed) each comprising two rolls having a crossed or skew axis. One of these rolls has two separated bearing surfaces and is conveniently formed by two conical, or substantially conical parts 10 meeting at the centre of the length of the roll and having their larger diameters at the outer ends of the roll. The other roll of each pass has a bearing surface located intermediate the two separated bearing surfaces of 15 the first-named roll and is smaller in length and diameter than the latter.

When two passes of the kind named are employed, these passes are separated and are disposed at a suitable distance apart. Each 20 of these pairs of rolls is a complete straightening pass in itself, especially adapted to remove short bends or kinks in rods and tubes, whilst the two passes prevent the rod or the like from swinging laterally without 25 the help of an auxiliary guiding means.

The rod or tube passing through the passes has two separate bearings on each of the larger rolls and a separate bearing on the smaller roll, a bending space being provided 30 at or about the centre of each of the larger rolls.

A third roll is provided in the machine, and this roll is similar in all respects to the smaller rolls previously described. This roll 35 will hereinafter be referred to as the pressure roll and is mounted in between the two smaller rolls and is located opposite the space between the two double conical larger rolls.

The small rolls and the pressure roll are all 40 preferably slightly concave on their bearing surfaces.

In this kind of machine the smaller rolls and the pressure roll have hitherto been each mounted in a yoke carried by a bracket having a slot arranged transversely to the axes 45 of the rolls, and the length of the machine, and a bolt was arranged to pass through this slot and through a longitudinal slot formed in the frame of the machine. In this way 50 provision was made for adjusting the rolls

longitudinally or transversely of the machine.

An arrangement of wedges mounted on a screwed shaft were provided and a wedge was adapted to engage with each of the brackets carrying the said yokes so that by rotating the screwed shaft the yokes carrying the two small rolls and the pressure roll could be each advanced or withdrawn transversely of the machine (that is to or from the larger rolls) to the same extent. To adjust the rolls longitudinally, the bolt passing through the bracket had to be released and the bracket slidden along, the bolt being then again screwed up.

In practice the rolls of a straightening machine are shaped to deal with a predetermined diameter of rod or tube, the arrangement being such that a comparatively large portion of the peripheral surfaces of the rolls engage the rod or tube as it passes through the machine.

Hitherto when such a machine was used for treating rods or tubes of diameters different to the said predetermined diameter such over or undersized rods or tubes were 75 not properly supported and could not be so properly supported by the primary rolls because the contours of these rolls were not in most cases entirely suitable for the rods being treated. Such definite support of the rods or tubes resulted in a slightly wavy or 80 sinuous formation being imparted to the rods or tubes, which wavy or sinuous formation is undesirable and especially is this so in some cases, for example where the rod or 85 tube is to be silver plated, because in this case the defect appears to be magnified after plating.

It is therefore one of the objects of this invention to provide a machine which will 90 straighten rods or tubes of a given range of sizes suitable for the machine and which will obviate or reduce to a minimum the above described sinuous or wavy defects in the treated rod or tube.

A further object of the invention is to 95 provide a generally improved means for adjusting the said small rolls and the pressure roll both transversely and longitudinally of the machine.

100

A further object of the invention is to provide further adjustments in the said rolls of the machine, and yet another object of the invention is to provide a generally improved rod and tube straightening machine.

5 Referring to the drawings:—

Figure 1 is a front elevation of one form of machine constructed according to this invention.

10 Figure 2 is a plan of the same.

Figure 3 is a longitudinal section on line 3—3 Figure 2.

15 Figure 4 is a part sectional plan of the machine shown in Figures 1 to 3.

Figure 5 is a transverse section on line 5—5 Figure 2.

20 Figure 6 is a part sectional elevation of a detail.

Figure 7 is a part sectional elevation of another detail, and

25 Figure 8 is a section on line 8—8 Figure 7.

In the machine illustrated in the drawings, 1 is the frame, 2 and 3, are the primary rolls, 4 and 5 are the secondary rolls, and 6 is the pressure roll. The primary rolls 2, 30 and 3, are carried respectively in yokes 7 and 8 on shafts 9 and 10. The secondary rolls 4 and 5 are each carried on a spindle in a separate yoke 11, whilst the pressure roll 6 is carried on a spindle in a yoke 12. The secondary rolls 4 and 5, and the pressure roll 6 are adjustable to and from the vertical plane containing the primary rolls 2 and 3, and the secondary rolls, and the 35 pressure roll are also angularly adjustable.

The yokes 7 and 8 carrying the primary rolls 2 and 3 respectively are made separately of the frame 1 of the machine and are each angularly adjustable about an axis perpendicular to the axis of its roll and are each provided with a central boss 13, mounted rotatably in a correspondingly shaped recess in the frame 1 of the machine.

40 Each yoke 7 and 8 is provided with flanges 14 having arcuate slots 15 through which pass bolts or studs 16 screwing into the frame 1 and serving to lock the yoke in an angularly adjusted position.

45 In some cases worms 17 and 18 may be provided on a horizontal shaft 19 adapted to be rotated by a hand wheel 20 for rotating for adjustment purposes the yokes 7 and 8, worm wheel teeth being provided on, or associated with the flanges 14 of the yoke 7 and 8 respectively for engaging with the worms 17 and 18. This worm and worm wheel method of adjustment is not absolutely necessary and may or may not be used as desired.

50 The primary rolls 2 and 3 are driven from a suitable power source such as an electric motor 21 through the medium of a driving shaft 22 mounted in bearings 23 and 24 carried by the frame 1 of the machine. The shaft 22 is provided with a pair of worms 25, 55 and these worms each gear with a worm

wheel 26. Each worm wheel 26 is mounted on a horizontal shaft 27 mounted transversely of the machine and being disposed one on the centre line of each of the yokes 7 and 8. The inner end of each of the shafts 70 27 carries a bevel wheel 28 which meshes with a further bevel 29 carried on a longitudinal shaft 30 mounted in the corresponding primary yoke of the machine.

The yoke has an axial recess 59 in which 75 the bevels 28 and 29 are housed.

It should be understood that the method of driving each of the primary rolls 2 and 3 is the same and therefore the drive for the roll 2 only will be described.

80 The shaft 30 is mounted in the primary yoke parallel to the shaft carrying the primary roll, and the latter shaft and the shaft 30 are geared together by spur gears 31 enclosed in a gear case 32 forming part of, or carried by, the primary yoke.

The frame 1 of the machine may be made in any number of parts so as to permit of easy assembly, or dismantling of the machine, and for the proper enclosure of the gears.

90 The shafts 9 and 10 carrying the primary rolls 2 and 3 respectively are mounted on roller bearings 33 mounted in the corresponding yoke and in order to prevent scale and débris generally, getting to these bearings 95 and thereby damaging them, a cover plate 34 is provided at each end of each roll, and this plate is bolted or otherwise secured to the yoke carrying the roll, whilst the other end of the cover plate engages in a recess 35 in the 100 adjacent end of the roll, and a packing washer 36 of felt or other suitable material is placed in a groove in the cover plate 34 so as to make a dirt proof joint between the roll and the plate, whilst not hindering the proper rotation of the roll. Oil grooves 37 may be provided on the inside of the cover plate.

105 The arrangement described permits of the primary rolls being adjusted angularly so as to enable the straightening machine to be 110 used with a variety of sizes of rod or tube, the adjustment enabling the rolls to be adjusted into the position of maximum engagement with any particular rod or tube.

115 The front of the frame 1 of the machine is provided with a longitudinal slot or guideway 38 extending horizontally of the frame of the machine within a suitable distance of each end thereof. This slot is provided with suitable facings on its inside, and its edges are longitudinally chamfered at 39 and 40. In this slot 38 are mounted three slides 41, one of these slides being provided for each of the secondary rolls 4 and 5, and one for the pressure roll 6. Each slide is of rectangular shape in cross section and is provided at one end with a flange 42 chamfered on its inner surface to correspond with the chamfered edge of the said longitudinal slot 38, and the slide is adjustable longitudinally in 120 125 130

the slot 38. The slide does not extend all the way through the slot in the frame but is rather shorter than the width of the said slot, as is clearly seen from Figure 7 of the drawings.

5 A central bore 43 is provided in each of the slides 41, and the axis of this bore is preferably at right angles to the longitudinal plane of the slot 38 in the frame.

10 Each of the yokes 11, 11 and 12 is provided with a cylindrical shank 44 adapted to enter the bore 43 in the corresponding slide 41.

15 In turn each shank 44 is provided with an axial bore 45 in which is mounted rotatably, but axially immovably, the reduced inner end 46 of a screw threaded spindle 47, this spindle being co-axially disposed in relation to the shank 44. A spindle 47 is provided for each of the yokes 11, 11 and 12, 20 and a hand wheel 48 is provided on the outer end of each spindle.

25 Each of the spindles 47 is mounted rotatably in an internally screw threaded clamping plate 49 adapted to be secured to the corresponding slide 41 by means of set screws 50, these set screws passing through the clamping plate and engaging in the slide.

30 A lock nut 60 is provided on each spindle 47 for locking the spindle in an adjusted position in its clamping plate 49.

35 The upper and lower edges of the clamping plate 49 are chamfered to suit the corresponding edges of the longitudinal slot 48 in the frame 1. By tightening up the set screws 50 the slide 41 and clamping plate 49 are drawn together so as to clamp the frame of the machine between them and secure the yokes 11, 11 and 12 in their respective adjusted longitudinal positions.

40 Rotation of each of the hand wheels 48 causes the corresponding spindle 47 to be moved transversely of the machine in its clamping plate 49, thus causing the corresponding yoke 11, 11, or 12 to be moved transversely of the machine, that is to or from the vertical longitudinal plane of the primary rolls 2 and 3, the direction of movement of the said yokes depending on the direction of rotation of the spindle 47. The position of the yokes are adjusted longitudinally of the machine by means of the slides 41, clamping plates 49 and studs 50.

45 In addition to the two adjustments described i. e. the longitudinal and transverse adjustments, the yokes 11, 11 and 12 are angularly adjustable. This adjustment is effected by turning the shank 44 carrying the yoke in its bearings in the corresponding slide.

50 The means provided for locking each of the yokes 11, 11 and 12 in an angularly adjusted position comprises an annular plate 51 mounted on the shank 44 on the yoke between the yoke and the corresponding slide

55 41. The shank 44 is provided with a longitudinal key-way 52 and a feather key 53 is slidable in this key-way and engages in a key-way 54 provided in the plate 51 so that the shank 44 is slidable in the latter but is 70 not rotatable separately of the plate 51.

75 The annular plate 51 is provided with one or more arcuate slots 55 (see Figure 8) and a set screw 56 passes through each of these slots and engages in the adjacent slide 41. When the angular position of the yoke 11, 11 or 12 is to be adjusted the set screws 56 are slackened the yoke is rotated to the required position and the set screws 56 are again tightened.

80 Worm, bevel, and spur gears have been shown in the drawings for transmitting the drive to the primary rolls, but it should be understood that spiral or helical gears may be used if desired.

85 With a machine constructed according to this invention the primary rolls are adjustable angularly, and so are the secondary and pressure rolls. This enables any one machine to be used effectively for a considerable variety of sizes of rods or tubes. Furthermore the secondary and pressure rolls can be adjusted either transversely or longitudinally of the machine in a better and quicker manner than has hitherto been possible, and at the same time easily and effectively.

90 I have described a machine having a pair of primary rolls, but it should be understood that the present invention is applicable to machines having a larger number of primary rolls.

95 100 What I claim then is:—

105 1. A rod and tube straightening machine of the type specified comprising, a frame, a primary roll, a secondary roll, said rolls forming a pass, a pressure roll, a yoke for each of said secondary and pressure rolls, and in which such rolls are rotatably mounted, a stem on said yoke, a slide for each of said secondary and pressure roll yokes, mounted adjustably in a longitudinal slot in the frame of the machine and in which the said yoke stem is mounted in an angularly and axially adjustable manner, and a screwed adjusting 110 spindle associated with said stem.

115 2. A rod and tube straightening machine of the type specified comprising, a frame, a primary roll, a secondary roll, said rolls forming a pass, a pressure roll, and said secondary and pressure rolls being separately angularly adjustable, and said secondary and pressure rolls being adjustable longitudinally and also transversely of the machine.

120 3. A rod and tube straightening machine of the type specified comprising, a frame, a primary roll, a secondary roll, said rolls forming a pass, a pressure roll, a yoke for each of said secondary and pressure rolls, and in which such rolls are rotatably mounted, a stem on 125

130

said yoke, a slide for each of said secondary and pressure roll yokes mounted adjustably in a longitudinal slot in the frame of the machine and in which the said yoke stem is mounted in an angularly and axially adjustable manner, a screwed adjusting spindle associated with said stem, a plate rotatable with said yoke stem but in which the stem is slideable endwise, said plate having a slot, and a locking stud adapted to pass through the slot in said plate and engage in said slide to lock said plate and stem in an adjusted angular position.

4. A rod and tube straightening machine of the type specified comprising, a frame, a primary roll, a secondary roll, said rolls forming a pass, a pressure roll, a yoke for each of said secondary and pressure rolls, and in which such rolls are rotatably mounted, a stem on said yoke, a slide for each of said secondary and pressure roll yokes mounted adjustably in a longitudinal slot in the frame of the machine and in which the said yoke stem is mounted in an angularly and axially adjustable manner, a flange on one end of said slide adapted to engage one side of the slotted part of the frame, a clamping plate associated with the other end of said slide and adapted to clamp the slide in a longitudinally adjusted position, a screwed adjusting spindle screwing into said clamping plate and connected to said stem so that the latter moves axially with the screwed spindle but so that either can rotate freely without the other, a plate rotatable with said yoke stem but in which the stem is slideable endwise, said plate having a slot and a locking stud adapted to pass through the slot in said plate and engage in said slide to lock said plate and stem in an adjusted angular position.

5. A rod and tube straightening machine of the type specified comprising, a frame, a primary roll, a yoke in which said primary roll is mounted, an axial boss on said yoke rotatably mounted in a correspondingly shaped recess in the machine frame, means for locking said yoke in an adjusted position, a longitudinal shaft in said yoke on which said primary roll is mounted, a second shaft in said yoke parallel to said primary roll carrying shaft and geared to the latter, a transverse shaft mounted in the machine coaxially with said yoke and geared to said second shaft, a driving shaft geared to said transverse shaft, and a secondary roll, said primary and secondary rolls forming a pass.

6. A rod and tube straightening machine of the type specified comprising, a frame, a primary roll, a yoke in which said primary roll is mounted, said yoke being mounted on said frame in an angularly adjustable manner, a flange on said yoke having a slot, a clamping stud passing through said slot and engaging in said frame and adapted to clamp

the yoke in an angularly adjusted position, and a secondary roll, said primary and secondary rolls forming a pass.

7. A rod and tube straightening machine of the type specified comprising, a frame, a primary roll, a yoke in which said primary roll is mounted, said yoke being mounted on said frame in an angularly adjustable manner, a flange on said yoke having a slot, a clamping stud passing through said slot and engaging in said frame and adapted to clamp the yoke in an angularly adjusted position, a longitudinal shaft in said yoke on which said primary roll is mounted, a second shaft in said yoke parallel to said primary roll carrying shaft and geared to the latter, a transverse shaft mounted in the machine coaxially with said yoke and geared to said second shaft, a driving shaft geared to said transverse shaft, and a secondary roll, said primary and secondary rolls forming a pass.

8. A rod and tube straightening machine of the type specified comprising, a frame, a primary roll, a yoke in which said primary roll is mounted, said yoke being mounted on said frame in an angularly adjustable manner, a flange on said yoke having a slot, a clamping stud passing through said slot and engaging in said frame and adapted to clamp the yoke in an angularly adjusted position, a longitudinal shaft in said yoke on which said primary roll is mounted, a second shaft in said yoke parallel to said primary roll carrying shaft and geared to the latter, a transverse shaft mounted in the machine coaxially with said yoke and geared to said second shaft, a driving shaft geared to said transverse shaft, a secondary roll, said primary and secondary rolls forming a pass, said secondary rolls being separately, angularly, longitudinally, and transversely adjustable.

9. A rod and tube straightening machine of the type specified comprising, a frame, a primary roll, a yoke in which said primary roll is mounted, said yoke being mounted on said frame in an angularly adjustable manner, a flange on said yoke having a slot, a clamping stud passing through said slot and engaging in said frame and adapted to clamp the yoke in an angularly adjusted position, a longitudinal shaft in said yoke on which said primary roll is mounted, a second shaft in said yoke parallel to said primary roll carrying shaft and geared to the latter, a transverse shaft mounted in the machine co-axially with said yoke and geared to said second shaft, a driving shaft geared to said transverse shaft, a secondary roll, said primary and secondary rolls forming a pass, a pressure roll, a yoke for each of said secondary and pressure rolls, and in which such rolls are rotatably mounted, a stem on said yoke, a slide for each of said secondary and pressure roll yokes mounted adjustably

- in a longitudinal slot in the frame of the machine and in which the said yoke stem is mounted in an angularly and axially adjustable manner, and a screwed adjusting spindle 5 associated with said stem.
10. A rod and tube straightening machine of the type specified comprising, a frame, a primary roll, a yoke in which said primary roll is mounted, an axial boss on said yoke 10 rotatably mounted in a correspondingly shaped recess in the machine frame, a flange on said yoke having a slot, a clamping stud passing through said slot and engaging in said frame and adapted to a clamp the yoke 15 in an angularly adjusted position, a longitudinal shaft in said yoke on which said primary roll is mounted, a second shaft in said yoke parallel to said primary roll carrying shaft and geared to the latter, a transverse 20 shaft mounted in the machine co-axially with said yoke and geared to said second shaft, a driving shaft geared to said transverse shaft, a secondary roll, said primary and secondary rolls forming a pass, a pressure 25 roll, a yoke for each of said secondary and pressure rolls, and in which such rolls are rotatably mounted, a stem on said yoke, a slide for each of said secondary and pressure roll yokes mounted adjustably in a 30 longitudinal slot in the frame of the machine and in which the said yoke stem is mounted in an angularly and axially adjustable manner, a flange on one end of said slide adapted 35 to engage one side of the slotted part of the frame, a clamping plate associated with the other end of said slide and adapted to clamp the slide in a longitudinally adjusted position, and a screwed adjusting spindle screwing 40 into said clamping plate and connected to said stem so that the latter moves axially with the screwed spindle but so that either can rotate freely without the other.
11. A rod and tube straightening machine of the type specified comprising, a frame, a primary roll, a yoke in which said primary roll is mounted, an axial boss on said yoke 45 rotatably mounted in a correspondingly shaped recess in the machine frame, means for locking said yoke in an adjusted position, a longitudinal shaft in said yoke on which said primary roll is mounted, a second shaft in said yoke parallel to said primary roll carrying shaft and geared to the latter, a transverse shaft mounted in the machine co-axial- 50 ly with said yoke and geared to said second shaft, a driving shaft geared to said transverse shaft, a secondary roll, said primary and secondary rolls forming a pass, a pressure 55 roll, a yoke for each of said secondary and pressure rolls, and in which such rolls are rotatably mounted, a stem on said yoke, a slide for each of said secondary and pressure 60 roll yokes mounted adjustably in a longitudinal slot in the frame of the machine and in which the said yoke stem is mounted in 65 an angularly and axially adjustable manner, a flange on one end of said slide adapted to engage one side of the slotted part of the frame, a clamping plate associated with the other end of said slide and adapted to clamp the slide in a longitudinally adjusted position, a screwed adjusting spindle screwing 70 into said clamping plate and connected to said stem so that the latter moves axially with the screwed spindle but so that either can rotate freely without the other, a plate rotatable with said yoke stem but in which the stem is slidable endwise, said plate having a slot, a locking stud adapted to pass through the slot in said plate and engage in said slide to lock said plate and stem in an adjusted 75 angular position, and covers over the bearings of the rolls.
12. A rod and tube straightening machine of the type specified comprising, a frame, a primary roll, a yoke in which said primary 80 roll is mounted, an axial boss on said yoke 85 rotatably mounted in a correspondingly shaped recess in the machine frame, a flange on said yoke having a slot, a clamping stud passing through said slot and engaging in said frame and adapted to clamp the yoke 90 in an angularly adjusted position, a longitudinal shaft in said yoke on which said primary roll is mounted, a second shaft in said yoke parallel to said primary roll carrying shaft and geared to the latter, a transverse 95 shaft mounted in the machine co-axial- 100 ly with said yoke and geared to said second shaft, a driving shaft geared to said transverse shaft, a secondary roll, said primary and secondary rolls forming a pass, a pressure 105 roll, a yoke for each of said secondary and pressure rolls, and in which such rolls are rotatably mounted, a stem on said yoke, a slide for each of said secondary and pressure roll yokes mounted adjustably in a longitudinal slot in the frame of the machine and in which the said yoke stem is mounted in 110 an angularly and axially adjustable manner, a flange on one end of said slide adapted to engage one side of the slotted part of the frame, a clamping plate associated with the other end of said slide and adapted to clamp the slide in a longitudinally adjusted position, a screwed adjusting spindle screwing 115 into said clamping plate and connected to said stem so that the latter moves axially with the screwed spindle but so that either can rotate freely without the other, a plate rotatable with said yoke stem but in which the stem is slidable endwise, said plate having a slot, a locking stud adapted to pass through the slot in said plate and engage in said slide to lock said plate and stem in an adjusted 120 angular position, and covers over the bearings of the rolls.
13. A rod and tube straightening machine of the type specified comprising a frame, a primary roll, a yoke in which said primary 125 roll is mounted, an axial boss on said yoke 130 rotatably mounted in a correspondingly shaped recess in the machine frame, a flange on said yoke having a slot, a clamping stud passing through said slot and engaging in said frame and adapted to clamp the yoke in an angularly adjusted position, a longitudinal shaft in said yoke on which said primary roll is mounted, a second shaft in said yoke parallel to said primary roll carrying shaft and geared to the latter, a transverse shaft mounted in the machine co-axial- 135 ly with said yoke and geared to said second shaft, a driving shaft geared to said transverse shaft, a secondary roll, said primary and secondary rolls forming a pass, a pressure roll, a yoke for each of said secondary and pressure rolls, and in which such rolls are rotatably mounted, a stem on said yoke, a slide for each of said secondary and pressure roll yokes mounted adjustably in a longitudinal slot in the frame of the machine and in which the said yoke stem is mounted in 140 an angularly and axially adjustable manner, a flange on one end of said slide adapted to engage one side of the slotted part of the frame, a clamping plate associated with the other end of said slide and adapted to clamp the slide in a longitudinally adjusted position, a screwed adjusting spindle screwing into said clamping plate and connected to said stem so that the latter moves axially with the screwed spindle but so that either can rotate freely without the other, a plate rotatable with said yoke stem but in which the stem is slidable endwise, said plate having a slot, a locking stud adapted to pass through the slot in said plate and engage in said slide to lock said plate and stem in an adjusted angular position, and covers over the bearings of the rolls.

- roll is mounted said yoke being mounted on said frame in an angularly adjustable manner, a flange on said yoke having a slot, a clamping stud passing through said slot and 5 engaging in said frame and adapted to clamp the yoke in an angularly adjusted position, a longitudinal shaft in said yoke on which said primary roll is mounted, a second shaft in said yoke parallel to said primary roll carrying shaft and geared to the latter, a transverse shaft mounted in the machine co-axially with said yoke and geared to said second shaft, a driving shaft geared to said transverse shaft, a secondary roll, said primary 10 and secondary rolls forming a pass, and bearing covers each adapted to make a dirt proof joint with an end of the primary roll.
14. A rod and tube straightening machine of the type specified comprising, a frame, a 15 pair of spaced primary rolls, a secondary roll for each primary roll, a pressure roll disposed between said secondary rolls and opposite the space between the primary rolls, said primary, secondary and pressure rolls being angularly adjustable, and said secondary and pressure rolls being adjustable longitudinally and also transversely of the machine.
15. A rod and tube straightening machine of the type specified comprising a frame, a 20 pair of spaced primary rolls, a secondary roll for each primary roll, each pair of opposite primary and secondary rolls being adapted to form a pass, a pressure roll disposed between said secondary rolls and opposite the 25 space between the primary rolls, a yoke for each primary roll and in which the primary roll is rotatably mounted, an axial boss on said yoke rotatably mounted in a correspondingly shaped recess in the machine frame, a 30 flange on said yoke having a slot, a clamping stud passing through said slot and engaging in said frame and adapted to clamp the yoke in an angularly adjusted position, a longitudinal shaft in said yoke on which said primary 35 roll is mounted, a second shaft in said yoke parallel to said primary roll carrying shaft and geared to the latter, a transverse shaft mounted in the machine co-axially with said yoke and geared to said second shaft, a 40 driving shaft geared to said transverse shaft, a yoke for each of said secondary and pressure rolls, and in which such rolls are rotatably mounted, a stem on said yoke, a slide for each of said secondary and pressure roll yokes 45 mounted adjustably in a longitudinal slot in the frame of the machine and in which the said yoke stem is mounted in an angularly and axially adjustable manner, a flange on one end of said slide adapted to engage one 50 side of the slotted part of the frame, a clamping plate associated with the other end of said slide and adapted to clamp the slide in a longitudinally adjusted position, a screwed adjusting spindle screwing into said clamping 55 plate and connected to said stem so that the 60

latter moves axially with the screwed spindle but so that either can rotate freely without the other, a plate rotatable with said yoke stem but in which the stem is slidable endwise, said plate having a slot, a locking stud adapted to pass through the slot in said plate and engage in said slide to lock said plate and stem in an adjusted angular position, and bearing covers each adapted to make a dirt proof joint with an end of the primary roll.

75

16. A rod and tube straightening machine of the type specified comprising a frame, a pair of spaced primary rolls, a secondary roll for each primary roll, a pressure roll disposed between said secondary rolls and opposite the space between the primary rolls, said primary, secondary, and pressure rolls being angularly adjustable, mechanical means for angularly adjusting said primary rolls and said secondary and pressure rolls being adjustable longitudinally and also transversely of the machine.
